MOTH REPELLENT CONTAINER

Evelyn D. Werner, Hastings-on-Hudson, N. Y.
Application January 3, 1957, Serial No. 44,384

Term of patent 14 years

(Cl. D31—3)

Fig. 1

Fig. 3

Fig. 2

Fig. 4

Fig. 1 is a perspective view of a moth repellent container showing my new design;

Fig. 2 is a front elevational view of Fig. 1 on a reduced scale;

Fig. 3 is a side elevational view of Fig. 2;

Fig. 4 is a bottom plan view of Fig. 2.

I claim:

The ornamental design for a moth repellent container, as shown.
